QUANTITATIVE DETERMINATION OF
METALS

Gerold Schwarzenbach, Zurich, Switzerland, assignor to Chemische Fabrik Uetikon (Uetikon Chemical Company), Uetikon, Switzerland, a firm of Switzerland

No Drawing. Application April 8, 1946, Serial No. 660,408. In Switzerland May 2, 1945

12 Claims. (Cl. 23—230)

1

For the quantitative determination of numerous metals and, especially, of the alkaline-earth metals, at the present time only gravimetric and indirect titrimetric methods are available. Thus, for example, for the determination of the total hardness of a natural water by the standard method, a sample thereof is treated with an excess of a standard solution of sodium carbonate and sodium hydroxide, in order to precipitate the calcium as carbonate. This is effected either by evaporating the mixture to dryness or letting it stand for a day. In the former case it is taken up in distilled water. The whole is then filtered and the filtrate is titrated back with hydrochloric acid of known strength. The total hardness can be calculated from the volumes of the sample of water employed, the added solution of sodium carbonate and sodium hydroxide and the hydrochloric acid needed for the back titration. This method is very complicated and tedious. In addition, the result is obtained as a difference between two comparatively large figures and therefore lacks accuracy. The other known methods for determining the total hardness are either similarly troublesome or are suitable only for approximate determination of hardness as, for example, in the case of Blacher's method in which a soap solution is employed.

It has now been found that the total hardness of any water can be determined in a particularly simple and reliable manner by adjusting to the same pH value a sample of the water and a solution of an amino polycarboxylic acid compound containing in relation to one basic nitrogen atom more than one carboxymethyl group attached directly thereto, said compound being capable of sequestering calcium in complex form, mixing with the sample of water an amount of the solution of amino polycarboxylic acid compound at least sufficient to sequester in soluble complex form the metal cations such as calcium and magnesium responsible for water hardness, and then adding progressively a standard alkaline solution until the pH value of the mixture is restored to the value to which the water sample and the solution of amino polycarboxylic acid compound were initially adjusted.

It should be here pointed out that the hydrogen which is associated with the amino carboxylic compound is fairly tightly held and contributes virtually no acidity to the aqueous solution in which the amino carboxylic acid compound is employed. When the solution is added to the water sample, and the metal ions react with the amino carboxylic acid compound, this hydrogen

5 is displaced and becomes an active hydrogen ion and thereby produces a proportionate drop in the pH value of the final solution. Consequently, by titrating the solution with a standard alkaline solution such as dilute sodium hydroxide solution, until the pH value of the sample is restored to its original adjusted value which existed prior to the addition of the complex-forming amino polycarboxylic acid compound, the volume of alkali solution required to neutralize the liberated acid represents the equivalent of hardness present in the water sample.

10 The pH adjustment of the original water sample and that of the amino polycarboxylic acid compound may be readily effected either electrometrically or more simply with the aid of one of the well-known acid-base colorimetric indicators, for example methyl orange, methyl red, phenolphthalein, etc.

15 In addition to calcium, the other alkaline-earth metals, and also lithium, aluminium the rare-earth metals, zinc, cadmium, mercury, lead, copper, iron, cobalt, nickel and manganese can be quantitatively determined by the same 20 method. Especially suitable as complex-forming compounds are the aminopolycarboxylic acids of the general formula

30 wherein R stands for a member selected from the group consisting of hydrogen and the radicals $-\text{CH}_2\text{COOH}$,

40 and

50 Iminodiacetic acid, nitrilotriacetic acid, anthranilic-acid-diacetic acid, ethylenediamine-tetraacetic acid, examples within the general formula, have long been known, whilst aminomalonic-acid-diacetic acid and uramildiacetic acid have recently been prepared by me (Helvetica chimica acta 28, 1141 (1945); 29, 368 (1946)).

3

The following are suitable as complex-forming compounds: the salts of iminodiacetic acid, and of its derivatives, for example, nitrilotriacetic acid, anthranilic-acid-diacetic acid, ethylenediamine-tetracetic acid, and especially of uramildiacetic acid and aminomalonic-acid-diacetic acid. The latter two compounds have hitherto been unknown. On addition to the sample of one of the compounds just mentioned, a complex ion containing the metal being determined is formed. The metal ions are no longer present in their original state but are sequestered or locked up in the complex. Concurrently there is liberated an amount of acid equivalent to the metal which is sequestered, the acid becoming free and titratable as previously explained.

Apart from its simplicity and reliability, the importance of the new method lies in the fact that it enables a considerable number of metals to be titrated with the same standard alkaline solution as that used for the usual alkalimetric titrations. No special chemicals or apparatus are necessary for these determinations in addition to the complex-forming substances mentioned. Also, some of the complex-forming compounds are easily obtainable in an excellently crystalline form and in a condition of absolute purity and are therefore pre-eminently suitable as substances for titrimetric standards with the aid of which the alkaline and all other standard solutions are readily adjustable. The accuracy of the metal determinations is increased by the employment of such adjusted standard alkaline solutions. As a modification of the method outlined above, instead of adding a standard alkali solution and titrating with the aid of one of the acid-base colorimetric indicators mentioned, any one of a number of colorimetric indicators particularly suitable for determination of pH may be added to a solution, for example, containing water sample and complex-forming compound. The choice of indicator will be dependent upon the pH range in which the analysis is being conducted. In this alternative method, pH value of both sample and complex-forming solution are previously adjusted to identical level. When the indicator is added and thoroughly mixed with the aqueous solution, the indicator responds immediately by changing color. The color of the indicator represents a certain pH value or hydrogen-ion concentration which is readily ascertainable by comparison of the solution with a color scale of known values. The pH value may also be measured by electrometric means. The decrease of pH value due to liberation of acid upon addition of complex-former to the water sample is a measure of the total hardness present in the water sample. The above subject matter is claimed in my divisional, co-pending application, Serial No. 195,473, filed November 13, 1950.

It has further been found that the concentration of the various metals above enumerated can also be determined by titrating a solution containing the metal ion with a standard solution of an alkaline-reacting salt of one of the complex-forming compounds. Here no acid is liberated by the reaction between the metal ion and the complex-former as in the preceding examples. Instead, so long as all the metal ions have not reacted with the polycarboxylic acid salt to form a complex, the pH value of the solution will remain substantially unchanged. However, when a balance or equilibrium is reached and all of the metal ions have been united with the

65

70

75

4

complex-former, the next increment of alkali complex-former solution will cause a readily detectable increase in pH value which can be rendered visible by means of a suitable indicator. Thus, cobalt, nickel, zinc, copper and lead can be titrated very accurately with the tripotassium salt of nitrilotriacetic acid, whilst, for cadmium and manganese, it is better to employ the tetrapotassium salts of ethylenediamine tetracetic acid as standard solution. The pH values of the end points at which the indicator is to change colour, are different for the different metals and lie between 5 and 9. The determination of the end point of the titration can also, in all cases, be effected potentiometrically by means of an indicator electrode.

It has furthermore been found that in the titration of metals by means of a standard solution of the complex-forming compound, there can also be employed an indicator which responds directly by color change to the ions of the metal to be determined, some of these metal ions combining directly with the indicator itself. Thus, for example, iron and cobalt can be titrated with the complex-former using thiocyanate as the indicator and taking as the end-point the vanishing red or blue coloration depending upon the metal ion present. For determining zinc, for example, the diphenylthiocarbazone known by the name "dithizone" may be employed as an indicator. Especially impressive is the titration of calcium with murexide as the indicator. Murexide (ammonium purpurate) gives a blue color in alkaline solution and a red color in the presence of calcium. Accordingly, if a solution of a calcium salt and murexide, said solution having been rendered alkaline, is titrated with a standard solution of the complex-forming compound, the red color of the indicator changes to blue-violet as soon as all of the calcium ions have been combined with the complex-forming compound. Such an indicator functions on an entirely different basis than pH indicators. The latter respond solely to pH changes while the former undergo color change in solution in the presence of the metal or metals to be detected. The change in color occurs when analyzing for calcium by this method since the complex-forming compound ties up all of the uncombined calcium in solution and finally extracts the calcium which had previously combined with the murexide indicator. When this final extraction of the previously combined calcium occurs, the indicator changes color. Since the murexide does not respond to magnesium ions, this method is suitable for the determination of calcium in the presence of magnesium.

For these determinations of metals, there is advantageously selected from the complex-forming compounds mentioned a compound having an equilibrium constant of formation of the complex with the metal to be determined which is as large as possible and amounts to, at least, 100.

Examples

1. A natural water, the calcium content of which, according to the known standard method hereinbefore mentioned, amounted to 24.4 French degrees, was to be analysed. A sample measuring 200 cc. was, after the addition of methyl red, brought to a pH value of 5 with the addition of 0.02N hydrochloric acid. Incidentally, the number of cc. required for this purpose, divided by 2, gives the temporary hardness. After treatment with 10 cc. of a solution, which

contained 20 gms. of uramildiactic acid per litre, neutralised to a pH value of 5, the solution, which became acid, was titrated with 0.02N caustic soda solution until the color of the solution was the same shade of color as that of the original water sample after addition of methyl red and the 0.02N hydrochloric acid. 24.3 cc. were required, corresponding to a total hardness of 24.3 French degrees. Instead of methyl red, bromocresol purple can be employed with the same success.

If ethylenediamine-tetracetic acid is employed instead of uramildiactic acid, twice the amount to 0.02N caustic soda solution is required, so that the number of cc. of standard solution run in is to be divided by 2 to obtain the total hardness in French degrees. Thus, 200 cc. of the same water, after adjustment to a pH value of 5 and subsequent addition of a solution of ethylenediamine-tetracetic acid, the pH value of which also amounted to 5, required 49.0 cc. of 0.02N caustic soda solution, corresponding to a hardness of 24.5 French degrees.

2. A sample of 200 cc. of the natural water employed in Example 1 was treated with 10 cc. of normal caustic soda solution, a few drops of an aqueous solution of murexide were added and the whole was titrated with a strongly alkaline solution of the complex-forming compound until a color change took place from red to blue-violet. The standard solution employed was one containing 5.84 gms. of ethylenediamine-tetracetic acid. Only the calcium but not the magnesium, is determined by the change of color of the murexide, so that only the calcium hardness is obtained, because this standard solution causes the calcium ion to disappear before the magnesium ion.

3. For the purpose of determining the lead in a solution, produced by dissolving 6.96 gms. of the purest lead chloride per litre, 20 cc. were treated with 1 gm. of sodium chloride and, after the addition of methyl red, were brought to a pH value of 5 with caustic soda solution. 40 cc. of a m./40 solution of ethylenediamine-tetracetic acid, which also had a pH value of 5, were then added and the solution was titrated back with 0.05N caustic soda solution to a pH value of 5, for which purpose 19.9 cc. of the standard solution were necessary. The calculated quantity of lead was 0.103 gm., whilst 0.1025 gm. was found.

4. For the purpose of determining zinc, there were employed 20 cc. of a 0.1 m. solution of zinc chloride the content of which was determined gravimetrically. After adding bromothymol blue, the whole was titrated with a standard solution of 0.1 m. of trisodium nitrilotriacetate until a very sharp change of colour took place. For this purpose, exactly 20 cc., i. e. exactly the theoretical quantity, were required. The standard solution was prepared by dissolving 19.1 gms. of the purest nitrilotriacetic acid, dried in vacuo, in 300 cc. of normal caustic soda solution and making up to one litre.

5. For the purpose of determining copper, 20 cc. of a 0.1 m. solution of cupric chloride and the same standard solution as in Example 4 were employed, but methyl red was employed as indicator. The color change was from lilac to pure blue. In order to reach this color change, 19.8 cc. of the standard solution were necessary, whilst theoretically 20 cc. should have been used.

The following are the formulae of the acids hereinbefore mentioned from which the complex-forming salts are produced:

What I claim is:

1. A method of volumetrically determining metal cations in solution which comprises titrating a measured amount of the solution with a solution containing a known concentration of an amino polycarboxylic acid compound, said compound having in relation to one basic nitrogen atom more than one carboxymethyl group directly attached thereto, until an end-point detectable by suitable indicating means is reached, said end-point being the point where all of the aforesaid metal cations are united with the anions of the amino polycarboxylic acid compound to form a complex ion thereof, the amount of amino polycarboxylic acid compound being a direct measure of the aforesaid metal cations present in solution.
2. A method of determining metal cations in solution which comprises titrating the solution with a solution containing a known concentration of a compound of an amino polycarboxylic acid compound of the general formula

where R is a member selected from the group consisting of hydrogen and the radicals

75 until an end-point detectable by suitable indicat-

7

ing means is reached, said end-point being the point where all of the aforesaid metal cations are united with the anions of the amino polycarboxylic acid compound to form a complex ion thereof, the amount of amino polycarboxylic acid compound being a direct measure of the aforesaid metal cations present in solution.

3. A method of volumetrically determining metal cations in solution which comprises titrating a measured amount of the solution with a solution containing a known concentration of an alkaline-reacting salt of an amino polycarboxylic acid compound, said compound having in relation to one basic nitrogen atom more than one carboxymethyl group directly attached thereto, until an end-point is reached, said end-point being the point where all of the aforesaid metal cations are united with the anions of the amino polycarboxylic acid compound to form a complex ion thereof, and being the point where there occurs an increase in pH value which is detectable by suitable indicating means, the amount of alkaline-reacting salt of amino polycarboxylic acid compound being a direct measure of the aforesaid metal cations present in solution.

4. A method according to claim 3 in which the amino polycarboxylic acid has the general formula

where R is a member selected from the group consisting of hydrogen and the radicals

and

5. A method according to claim 3 in which the amino polycarboxylic acid compound is a salt of ethylene diamine tetracetic acid.

6. A method according to claim 3 in which the amino polycarboxylic acid compound is a salt of uramildiaceitic acid.

7. A method according to claim 3 in which the aminopolycarboxylic acid compound is a salt of nitrilo triacetic acid.

8. A method of volumetrically determining metal cations in solution which comprises making the solution suitably alkaline, titrating a measured amount of the solution with a solution containing a known concentration of an amine polycarboxylic acid compound, said compound having in relation to one basic nitrogen atom more than one carboxymethyl group directly attached thereto, said titration being carried out in the presence of a suitable colorimetric indicator which is responsive to the presence and absence of the

14

8

aforesaid metal cations in solution, until a visible change in the color of the indicator occurs, said change occurring when all the aforesaid metal cations are combined with the anions of the amino polycarboxylic acid compound, there being substantially no change in the pH value of the solution, the volume of amino polycarboxylic acid compound being a direct measure of the amount of the aforesaid metal cations present in the original solution.

9. A method according to claim 8 in which the amino polycarboxylic acid has the general formula

where R is a member selected from the group consisting of hydrogen and the radicals

and

and salts thereof.

10. A method according to claim 8 in which the amino polycarboxylic acid compound is a salt of ethylene diamine tetraacetic acid.

11. A method according to claim 8 in which the amino polycarboxylic acid compound is a salt of uramildiaceitic acid.

12. A method according to claim 8 in which the amino polycarboxylic acid compound is a salt of nitrilo triacetic acid.
